CLAIM

The ornamental design for a footbed as shown and described.

DESCRIPTION

FIG. 1 is a bottom view of a footbed showing our new design;

FIG. 2 is a first perspective view thereof;

FIG. 3 is a front view thereof;

FIG. 4 is a rear view thereof;

FIG. 5 is a right side view thereof;

FIG. 6 is a left side view thereof; and,

FIG. 7 is a second perspective thereof.

The broken lines in FIGS. 1-7 are included for the purpose of illustrating portions of the footbed and form no part of the claimed design. The areas within broken lines shown inside the circular and oval shapes represent regions that form no part of the claimed design.

(Continued)

The text shown in broken lines in FIGS. 1, 2, and 7 is included for the purpose of illustrating any insertable text, and the specific text shown in broken lines forms no part of the claimed design.
